CAP

Grace de Wolf Rollins, New Rochelle, and Ernestine Hines Dobbs, Larchmont, N. Y.

Application January 16, 1935, Serial No. 2,000

2 Claims. (Cl. 2—198)

This invention relates to women's wear, particularly to caps, and among the objects of the invention is to provide a cap which is not complex, but on the contrary, may be easily fabricated, and, at the same time, be attractive as well as useful. The cap is particularly suited for informal wear at the beach, while motoring, yachting and while indulging in sports generally, and for use under all conditions which make it desirable to keep the hair in place; also for protecting the hair and affording protection to the eyes from the sun.

Another object of the invention is to produce a cap in a form which makes it acceptable for modern sports wear, which is relatively inexpensive and which can be easily adjusted and fitted to any style of hair dressing, and which can be made becoming and in keeping with modern styles. The cap is made from two principal parts including a piece of material of a triangular shape and to which a visor is attached in such a manner as to produce such disposition in the form of the material as will cause the same to accommodate itself to the head of the wearer in a neat and attractive manner.

In the drawing, Fig. 1 illustrates one manner in which material may be cut in preparing the same to form the cap.

Fig. 2 illustrates the finished cap as it would appear laid out upon the top of a flat surface.

Figs. 3 and 4 illustrate one manner in which the cap may be worn.

We preferably make the top covering or hood portion 10 of the cap from a triangular piece of material which is produced by cutting a substantially square piece of material on one of the diagonals from one corner to the opposite corner, and we have found that while the size of the material from which the triangular piece of material may be cut may vary somewhat, an ordinary bandana is very satisfactory. It is to be understood, however, that the material from which the cap is to be made may be prepared, cut and decorated in any manner suited to manufacturing requirements and that we choose to illustrate a simple manner of making the cap so that its advantages may be made readily apparent to anyone who should desire to make the cap. By suggesting a bandana, the applicability of the wide variety of designs which bandanas provide suggests many possibilities as, for example, making the top of the visor from the border or corner of the same bandana so as to match the border design of the visor with that of the hood portion.

The bandana (or other kind of material) should

be cut in a substantially straight line between opposite corners 11, 12, as illustrated in Fig. 1, or in close proximity to the corners, and it is an advantage of our invention that it is not necessary to shape the edge of the bandana which attaches to the visor in any particular manner. After the material for the hood portion has been prepared, the other portion of the square may be used to cover the stiff material which is used in the visor 14.

As illustrated in Figs. 1 and 2, the stiff material 15, for the visor, which may be of cardboard, buckram, or other like material, is cut in the form of a crescent and preferably is faced on both sides by either the same material from which the hood portion has been cut, or from other material having suitable color and design to properly match with the general color scheme and pattern of the complete cap. For example this material may be cut from the border or any other part which has the decoration desired, as at 16 and 17, Fig. 1.

The visor is attached to the head covering material in such a manner that the visor will lie in the middle portion of the head covering material opposite the corner 18 which is a right angle. The straight edge of the head covering material preferably is sewed directly to the inner curve of the visor, as illustrated in Fig. 2, with the result that a puckering or gathering of the material between the two ends 19, 20 of the visor results. This puckering or gathering results in draping the hood portion over the head of the wearer, starting from the line of intersection of the visor with the wearer's forehead.

The right angle corner 18 of the head covering material drapes down the back of the head, as illustrated in Fig. 4, and the two other corners 11, 12 are drawn together and tied in such a manner that the visor, as well as the head covering, is held firmly in place. The knot at the back of the head may be arranged in any manner to suit the wearer, and it is, of course, adjustable so that the head covering may be made to fit any size head. Also, if the head covering is to be used where it is windy, as when motoring or sailing, the tightness of the knot and the relation of the head covering may be appropriately adjusted.

What we claim is:

1. As an article of manufacture, a cap comprising a piece of material for fitting over the head of a wearer to keep the wearer's hair in place, said piece of material being in the form of an isosceles triangle having two like corners and another corner with adjacent edges at right angles to each other which is designed to drape

- downwardly at the back of the wearer's head and be held in place against the wearer's hair by the tying together of the other two corners of the triangular piece of material, and a visor attached 5 to said piece of material at the edge thereof which extends between the two like corners, said visor having a curved edge which is attached to the straight edge of the piece of material whereby the piece of material is puckered between the ends 10 of the visor to produce bulging of the material and cause training of the same over and about the forehead of the wearer when the cap is secured in place when the cap is in use.
2. As an article of manufacture, a cap comprising attached hood and visor portions which 15 provide a fullness in the hood portion adjacent to and in the vicinity of the visor portion for allowing for the conforming of the material of the hood

portion to the rounded fore-part of a wearer's head, said hood portion having ends extending substantially laterally of the cap from the ends of the visor and converging rearwardly from said ends so that the cap may be fastened to and cover a wearer's head upon the tying together of the ends over the downwardly extending rearward area of the hood portion at the back of the head, the inner edge of said visor portion being curved and attached to the material of the hood portion 10 along a line thereon different in configuration from that of the inner edge of the visor, the material forming the hood portion of the cap being provided with the desired fullness by its attachment to the relatively stiffer visor. 15
